UNITED STATES PATENT OFFICE.

WILLIAM J. MOORE, OF PHILADELPHIA, PENNSYLVANIA.

MOP.

Application filed May 5, 1923. Serial No. 636,788.

To all whom it may concern:

Be it known that I, WILLIAM J. MOORE, a citizen of the United States, residing at Philadelphia, in the county of Philadelphia and State of Pennsylvania, have invented certain new and useful Improvements in Mops, of which the following is a specification.

My invention relates to mops and its object is to provide a mop-holder and mop-cloth which may be readily detached from each other; a mop-cloth which will not lose its strands, and a mop-holder which will receive and hold a pair of mop-cloths, permitting a large mop-cloth to be made in two pieces and thereby facilitate its handling.

This object, and other advantageous ends which will be described hereinafter, I attain in the following manner, reference being had to the accompanying drawings in which

Figure 1 is a front elevation of a mop constructed in accordance with my invention,

Figure 2 a side view of Figure 1,

Figure 3 a plan view of Figure 1,

Figure 4 a central section through the mop-holder,

Figure 5 a perspective view of one of the sections which make up the body of the mop-holder,

Figure 6 a plan view of the strands of the mop-cloth showing the reinforcing band as it is applied to the strands,

Figure 7 a view similar to Figure 6 showing the reinforcing band stitched to the strands,

Figure 8 shows the reinforcing band and strands folded and stitched again and provided with eyelets for receiving the holding means of the mop-holder, and

Figure 9 a section through the reinforcing band and one of the eyelets.

Referring to the drawings, the mop-holder 1 is made in sections 2 and 3 secured together by rivets 4, each section being provided with a semi-circular socket-part 5 and a flat body-part 6 having catches 7 struck up therefrom. When the sections are riveted together the socket parts 5 form a socket 8 and the body parts 6 forms a body 9. The socket 8 receives a handle 10 which is secured thereto by rivets 11. Mop holding hooks 12 are secured to the opposite sides of the body 9 by rivets 13 which extend from the hook on one side of the body to the hook on the other side. A mop-cloth 14 is provided with openings 15 for receiving the

hooks 12. The hooks are locked to the body by the catches 7 as shown in Figures 1 and 3. The construction of the mop-cloth may be of any suitable character but preferably as shown in Figures 6 to 9. The strands 16 of liquid-absorbing material are laid as shown in Figure 6 and a reinforcing band 17 placed around the strands. The band is secured thereto by any suitable means such as the stitching 18. A reinforcing core 19 is laid along the center row of the stitching 18 and the band and strands folded thereon and stitched again at 20 and 21. The folded sides 22 and 23 of the band are provided with the openings 15 which are reinforced by eyelets 24. If desired these openings may be reinforced by knitting around them.

When it is desired to remove the mop-cloths to wash them, the hooks are released from the catches 7 as shown in Figure 4 and the mop-cloths lifted off the hooks. By providing the mop-cloths in pairs, a large mop cloth is done away with and the handling of the cloths when washing them is facilitated. When the mop-cloths are worn on one side they may be turned around and used on the other side, thus lengthening the life of the cloth. By constructing the mop-cloth with a reinforcing band as above described, the strands will not pull out as was common in mop-cloths prior to my invention.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A mop holder including a body having a socket and a flat part depending edgewise from the socket; hooks attached to the sides of the body part and adapted to receive a mop cloth, and means on the body part adapted to engage the hooks to prevent the mop cloth from being accidentally pulled from the hooks.

2. A mop holder including a body having a socket and a flat part depending edgewise from the socket; catches on the sides of the body part, and hooks attached to the sides of the body part adapted to receive a mop

cloth and to be sprung into engagement with the catches to prevent the mop cloth from being accidentally pulled from the hooks.

3. A mop including a body; a handle on the body; a mop-cloth; hooks on the body for receiving the mop-cloth, and catches struck up from the body for locking the ends of the hooks to the body.
4. A mop including a body having a socket and made in sections, each section being provided with a semi-circular socket part, a flat body part, and catches struck up

from the flat body part; mop-cloths, and hooks on the body for receiving the mop-cloths and adapted to be locked to the body 15 by the catches.

In testimony whereof I have signed my name to this specification in the presence of two subscribing witnesses.

WILLIAM J. MOORE.
